UNITED STATES PATENT OFFICE.

LEO A. KRUPP, OF FINDLAY, OHIO, ASSIGNEE TO THE BUCKEYE TRACTION DITCHER COMPANY, OF FINDLAY, OHIO, A CORPORATION OF OHIO.

GEAR-SEGMENT FOR CUTTING-WHEELS.

1,173,261.

Specification of Letters Patent.

Patented Feb. 29, 1916.

Application filed May 14, 1915. Serial No. 28,005.

To all whom it may concern:

Be it known that I, LEO A. KRUPP, a citizen of the United States, and a resident of Findlay, in the county of Hancock and State of Ohio, have invented a certain new and useful Gear-Segment for Cutting-Wheels; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to excavating machines of the rotary cutting wheel type, and particularly to an improved segmental internal gear ring for the wheel.

In the use of machines of this character, the cutting wheel is customarily supported and guided in its rotation by flanged idler wheels, which engage the inner edge of each wheel rim so that such rims are thereby subject to considerable wear and quickly become worn to a feather edge, thus necessitating a replacing of the worn rings with new ones in order to maintain a rim mounting on the wheel and to perform satisfactory work. The cutting wheel is driven by spur drive pinions meshing with internal gear rings which are secured to the wheel rims adjacent to the inner edges thereof and are composed of segments riveted to the rims. It is thus evident that both the wheel rims and the gear segments are rapidly worn on account of the heavy work to which they are subjected and the abrasive nature of the material in which the wheel operates, thereby necessitating a frequent replacing of not only the gear segments but of the wheel rims.

The object of my invention is to obviate the wear on the wheel rims and to so construct and arrange the gear segments with respect to the wheel rims that all wear both from the driving of the cutting wheel and the supporting of the same by the idler wheels occurs on the gear segments, which are capable of being quickly replaced.

The invention is fully described in the following specification, and while, in its broader aspect, it is capable of embodiment in numerous forms, a preferred embodiment

thereof is illustrated in the accompanying drawings, in which—

Figure 1 is an outer side elevation of a gear segment embodying the invention. Fig. 2 is a side elevation of a cutting wheel with its guiding parts and with a portion of the gear segments removed and a portion in section. Fig. 3 is a cross-section of one rim of the wheel and through the respective combination drive pinion and guide-wheel, and Fig. 4 is an enlarged section of a rim and gear segment with a guide-wheel in engagement therewith, portions of the rim and guide wheel being broken away.

Referring to the drawings, 1 designates a cutting wheel of the type commonly used in ditching or excavating machines of the rotary type, this wheel being formed of two transversely spaced rims 2, which carry and are connected at their outer edges by excavating buckets 3, as well understood in the art. The cutting-wheel is supported at each side thereof by a set of flanged idler rolls 4 and by a flange or hub portion of the drive pinion 5, which rolls and pinion flange have heretofore engaged directly with the inner edge of the respective wheel rim. The guide rolls 4 and drive pinion 5 are supported by a frame 6 between the side beams of which the cutting-wheel is mounted.

The feature comprising my invention resides in the segments of the internal gears 7, which are riveted or otherwise suitably attached to the inner edge portion of each wheel rim 2 and mesh with respective drive pinions 5. Each segment of an internal gear 7 is composed of a body part 8, which is intended to seat against the outer side of a rim and has its inner edge inwardly flanged, as at 9, to extend under and entirely across the inner edge of the rim, said flange 9 cooperating with the inner edge of the body part 8 to form a broad internal bearing surface. The gear segments are provided near their outer edges with outwardly projecting teeth 10, which are equidistantly spaced and form gear teeth with which the teeth of the respective drive pinions 5 engage. The distance between the inner edges of the gear segments and the teeth 10 is sufficient to permit the flanges 4^a of the guide wheels 4 to lap the inner edges of the body portion of the gear segments without having contact

with the teeth. Each drive pinion 5 is intended to perform the function of both a drive pinion and a wheel guiding roll, and for such purpose is provided with a flange or hub enlargement 5^a which has rolling contact with the inner flanged edges of the gear segments.

It is evident that the provision of gear segments of this style enables such segments 10 to fit around the inner edges of the wheel rims whereby to protect the rims from wear and to provide a broad track for the guide rolls to engage with, as well as a much stronger construction for the wheel.

15 I wish it understood that my invention is not limited to any specific construction, arrangement or form of the parts, except in so far as such limitations are specified in the claims.

20 Having thus described my invention, what I claim as new, and desire to secure by Letters Patent, is,—

25 1. A cutting-wheel of the class described comprising spaced rims and having segmental internal gears secured thereto adjacent to their inner edges and embracing the inner edges of the rims to provide broadened roller bearing surfaces therefor.

2. The combination with a side rim of a cutting-wheel of the class described, and 30 bearing and guide rolls for said rim, of a segmental internal gear secured to a side of said rim with its teeth projecting outwardly therefrom, the segments of said gears having their inner edges inwardly flanged and ex- 35 tending across the inner edge of the rim to form a broadened guide roll bearing surface.

3. In a machine of the class described, the combination with a cutting-wheel having annular side rims, and an internal guiding and supporting means for said rims, of an internal gear secured to the inner edge portion of each rim at the outer side thereof and comprising a plurality of segments each of 40 which has a body portion which is secured to the outer side of the rim and has its inner edge flanged over the inner edge of the rim to form a broadened bearing surface for said 45 guide means and to protect the rim from wear, and teeth projecting outwardly from said body portion in spaced relation to the inner edge thereof.

In testimony whereof, I have hereunto signed my name to this specification.

LEO A. KRUPP.
